ELECTRIC RECORDING AND REPRODUCING APPARATUS

Adolph A. Thomas, New York, N. Y., assignor to
 Radio Corporation of America, New York, N. Y.,
 a corporation of Delaware

Application July 15, 1930, Serial No. 468,074

6 Claims. (Cl. 179—100.11)

My invention relates to the art of recording and reproducing sound, and its main object is to provide a unitary household cabinet which combines the functions of radio receiver, sound recorder, and phonographic reproducer. These various operations are selectively controllable by merely actuating a finger piece.

One feature of my invention comprises means for automatically recording a piece of radio broadcast simultaneously with its reproduction by the receiver through the loudspeaker. Sometimes it is desirable to make a record of an unusual broadcast number, like a song by a great artist, or the speech of a famous person. The recording is preferably done on a steel tape or wire by electromagnetic action, but it is also possible to record optically on a photographic film or mechanically on a wax record. The practical advantage of recording on a steel tape or wire lies in the fact that this record is permanent without further treatment and can be used immediately for reproduction through the loudspeaker of the radio receiver. The recording operation is silent and does not interfere with the normal function of the receiver, which can be used independently of the recording mechanism.

It is also possible to operate the recording mechanism of my cabinet while the receiver is cut out, although some of the receiver circuits are utilized during the recording operation. By simply throwing a switch, a person connects a telephone transmitter to the input circuit of the radio receiver, and at the same time he connects the recording device in the output circuit in place of the loudspeaker. It is now only necessary to talk or sing into the transmitter, and the sound is recorded on the steel tape, photographic film, wax record, or whatever recording device is employed. In this way it is easy to make really good records at home of the voices of members of the family, friends or visitors. Of course, the reproducing part of the machine can be operated by records made elsewhere, so that the machine can be used like a regular phonograph. By using the circuits of the radio receiver in the recording and reproducing operations, I require but little mechanism in addition to the receiver, so that the cabinet can be made compact and at a reasonable cost.

The novel features and practical advantages of my invention will be understood from a description of the accompanying drawings, in which—

Fig. 1 illustrates a cabinet containing my novel

combination of radio receiver, recorder and reproducer;

Fig. 2 is a plan view of the reproducing mechanism;

Fig. 3 is a transverse view along the broken 5 line 3—3 of Fig. 2;

Fig. 4 represents a front elevation of the recording mechanism, sectioned in part along the line 4—4 of Fig. 2;

Figs. 5 and 6 are enlarged fragmentary views 10 of a recording steel tape passing between the poles of an electromagnet, the first view being longitudinally of the tape and the other view transversely thereof;

Fig. 7 is an enlarged fragmentary view showing a pair of switch arms operated by the recording tape or film; 15

Fig. 8 is a diagram of circuits controlled by the recording tape or film in its forward and reverse movements; and 20

Fig. 9 is a diagram of the interconnected circuits in the cabinet for utilizing the radio receiver during the recording and reproducing operations.

Referring to Fig. 1, there is a cabinet C of 25 suitable construction and design having a top board 10 on which the recording and reproducing mechanism R is mounted for easy access. The chamber above the top board 10 is sufficiently deep to permit closing of cover 12. Behind the 30 front panel 13 is a radio receiver adapted to be controlled by one or more hand knobs 14 in the usual way. Below the receiver is a loudspeaker L of any approved type, and one either side of the loudspeaker is a compartment 15 for holding record spools or other articles. Each compartment 15 is closed by a door 16, and an ornamental grille or screen 17 covers the loudspeaker diaphragm. The particular location of the various parts in the cabinet is not important, and will 35 obviously vary in cabinets of different design. It is probably most convenient to have the recording and reproducing mechanism R directly below the lid of the cabinet, like the turntable and 40 pickup in ordinary phonographs. 45

The motorboard 10 carries two brackets 18 and 19 for supporting a pair of rotary shafts 20 and 21, on which a pair of spools or reels 22 and 23 are mounted so as to rotate therewith. The 50 spools 22 and 23 are arranged in lateral alignment and support a recording tape or film 24, which in the present instance is supposed to represent a magnetic steel band or ribbon of such thinness as to be easily flexible for winding and unwind- 55

ing, very much like an ordinary movie film. In fact, the tape 24 may be a photographic film on which sound tracks are recorded optically by methods well known to experts. Since 22 is the original pay-out reel on which the recording tape is wound when the machine is started for recording or reproducing, it is necessary to permit easy insertion and removal of the reel. For this reason the forward end of the supporting shaft 26 is free and carries a pivoted latch 25 which may be aligned with the shaft when reel 22 is put into the machine or taken out. After reel 22 has been positioned on shaft 20, the latch 25 is swung at right angles and holds the reel against axial displacement. The other reel 23 need not be removable, because the tape 24 is always rewound on reel 22 when the end of the record track is reached, as will be explained in due course. I have therefore shown a retaining disk 21 or washer 21' mounted on the free end of shaft 21, but a pivoted latch like 25 may be used if desired.

I shall now describe the connections for driving the spools or reels 22 and 23 in reverse directions for unwinding and rewinding the record tape 24. A bracket 26 mounted on top board 10 has an upward arm 27 provided with bearings 28 and 29, and a second arm 30 on the bracket terminates in bearings 31 and 32. An electric motor 33 carries a bracket 34 which has a bearing 35 in alignment with bearing 28, and these two bearings support a rotary shaft 36 arranged transversely of the cabinet. The shaft 36 carries near its ends a pair of gears 37 and 38, which are secured to the shaft by cross-pins 39 or otherwise. The gear 37 is bevelled and arranged permanently in mesh with a bevel gear 40 fixed on a vertical shaft 41 which is supported in bearing 32. A sleeve 42 rotatably mounted on shaft 36 carries at one end a gear wheel 43 and at the other end a bevel gear 44, which is similar to bevel gear 37 and in mesh with the vertical gear 40. A collar 45 fixed on shaft 36 prevents axial displacement of sleeve 42 on shaft 36. The motor shaft 46 carries a worm or spiral pinion 47 arranged in permanent mesh with a worm wheel or spiral gear 48 fixed on the vertical countershaft 41. The motor shaft 46 always rotates in the same direction at high speed, but the bevel gears 37 and 44 rotate in opposite directions at properly reduced speed. Since the bevel gear 37 is keyed to shaft 36, while the opposite gear 44 is secured to the loose sleeve 42, it is evident that the two gears 38 and 43 always rotate in opposite directions. That is to say, gear 38 always rotates in the same direction as bevel gear 37 and gear 43 always rotates with bevel gear 44.

The horizontally aligned bearings 29 and 31 (see Fig. 3) support a rotary shaft 49 on which a clutch ring 50 is slidably mounted, as by means of a key 51 or otherwise. The clutch ring 50 carries a gear wheel 52 arranged to mesh alternately with gear wheels 38 and 43, depending upon the position of the clutch ring. Referring to Fig. 3, when gear 52 is in mesh with gear 43, the shaft 49 rotates in a direction to drive the tape or film 24 from left to right, as viewed in Figs. 2 and 4. This is the forward movement of the tape, and gear 43 may therefore be called the forward or unwinding gear. When the clutch gear 52 is in mesh with gear 38, the direction of shaft 49 is reversed to rewind the tape 24 from reel 23 onto the initial pay-out reel 22. It will therefore be convenient to refer to gear 38 as the reverse or rewinding gear.

The slidable clutch ring 50 and gear 52 are adjusted to forward and reverse positions by electromagnetic mechanism comprising a pair of coils 53 and 54, which actuate a pair of magnetic cores 55 and 56 connected to the lateral arms 57 of a bellcrank 58. A post 59 on bracket 26 carries a pivot pin 60 on which the bellcrank 58 is mounted for rocking movement in either direction. The upper end of bellcrank 58 is in the form of a yoke or bifurcated extension 61 which carries rollers arranged to engage in an annular groove 62 of clutch ring 50. A contracting coil spring 63 is connected at its upper end to bellcrank 58 and at its lower end to the supporting post 59. In either position of clutch ring 50, the tension line of spring 63 is to one side of the pivot axis of bellcrank 58, so that the latter is firmly held in either position by the spring. When the solenoid coil 53 is energized, the bellcrank 58 is rocked clockwise (as viewed in Fig. 3) to shift the clutch gear 52 into mesh with gear 43. When the other solenoid coil 54 is connected in circuit, the bellcrank 58 is rocked the other way to shift the clutch gear 52 into mesh with gear wheel 38. The two coils 53 and 54 may therefore be called the forward and reverse coils, respectively. To facilitate the intermeshing of clutch gear 52 with gear wheels 38 and 43, the teeth of these three gear members may be bevelled at the engaging edges, as shown in Fig. 3. By making these gear members of non-metallic material, such as re-enforced bakelite, fiber and the like, the operation of the gears is practically noiseless.

The shaft 49 carries a grooved pulley 64, which may be a single member with two grooves or two separate members with a single groove each. For convenience, however, I shall refer to the member 64 as a pulley having two grooves for receiving tensioned belts 65 and 66, which are preferably bands of elastic rubber, coiled springs, or the like. The pulley 64 is keyed to shaft 49 and always rotates therewith. The spool shaft 20 carries a grooved pulley 67 which receives the driving belt 65, whereby the spool 22 is operatively connected to shaft 49 for rotation in either direction. A bracket 68 on top board 10 supports a shaft 69 which carries a double grooved pulley 70. The rear end of the spool shaft 21 carries a grooved pulley 71 which is connected with pulley 70 by a tensioned belt or band 72, and the pulley 70 is connected to pulley 64 by belt 66. It is clear from Figs. 2 and 4 that the spools 22 and 23 are geared to shaft 49 for simultaneous rotation in the same direction as the shaft. The elastic belts 65, 66, and 72 allow sufficient slipping to compensate for the varying speeds at which the tape 24 is wound from one reel onto the other.

The spaced parallel shafts 49 and 69 carry sprocket wheels 73 and 74 adapted to engage the usual sprocket holes 75 at the edges of tape or film 24. The sprocket wheels 73 and 74 thus constitute direct and positive driving means for tape 24, so that the portion of the tape between the sprockets is fed in either direction at uniform predetermined speed, irrespective of any variations in the rate of take-up and unwinding of the tape by spools 22 and 23. To hold all portions of the tape or film 24 taut during the unwinding and rewinding movements, I provide automatic compensating arms 76 and 77 pivotally mounted on spool shafts 20 and 21. Each arm carries at its free end a lateral pin 78 for supporting a weighted roller 79 arranged to engage the record tape 24. Any slackness in tape 24 due to variations in the rate of winding and unwinding is automatically

taken up by the weighted rollers 79 which rise and fall as required. The rollers 79 are preferably covered with felt, rubber, or other material that will not injure the surface of tape 24.

5 As previously stated, the recording and reproducing tape 24 has been assumed to be a magnetic band or ribbon on which sound is recorded magnetically. In Fig. 8 the tape 24 carries two sound tracks 80 and 81, but any other number of sound tracks may be recorded. It is best to record an even number of tracks, so that the tape will be in rewound condition on reel 22 when the end of the last track is reached. This will become clear as the description proceeds. It goes without 10 saying that the sound tracks 80 and 81 are represented in Fig. 8 in a crude diagrammatic way, for the actual tracks are invisible and are nothing more than magnetic areas of varying intensity. The first sound track 80 begins at 80' and the 15 other sound track 81 begins at 81'. This means that in recording on track 80 and reproducing therefrom, the tape 24 runs forward in the direction of arrow 82 in Fig. 8; and for recording on and reproducing from the second sound track 81, 20 the tape is run in the reverse direction as indicated by arrow 83.

The electromagnetic mechanism for recording on steel tape 24 and reproducing therefrom comprises a U-shaped magnet 84 mounted in a non-magnetic frame 85, which is slidably supported between rollers 86 projecting laterally from bracket arms 87. These arms are secured to (or cast integral with) an upright post 88 mounted on the top board 10 of the cabinet. The field magnet 84 is provided with a pair of pole pieces 89 arranged in axial alignment and extending toward each other. One or each pole piece carries a coil 90 adapted to be connected in a circuit of variable electric impulses during the recording operation. 40 If two coils are used they are preferably connected in series as indicated in Fig. 8, but for convenience I shall consider the two coils as a single coil. The pole pieces 89 are arranged in axial alignment and may terminate in flat polar 45 projections 91 which touch a pair of fixed non-magnetic plates 92, as best shown in Figs. 5 and 6. The plates 92 are mounted on L-shaped arms 93, which may conveniently be secured to the horizontal bracket arms 87, as best shown in Figs. 50 4 and 7. The L-shaped arms 93 have horizontal extensions 93' to which the guide plates 92 are secured by screws 94 or otherwise. It is immaterial how the guide plates 92 are supported. The ends of plates 92 are preferably made divergent, as 55 indicated at 92' in Fig. 5, to facilitate the insertion of record tape 24.

The slidable frame 85 which carries the field magnet 84 has an extension 95 pivotally connected at 96 to the upper end of a bellcrank 97. The top 60 board 10 of the cabinet supports a block 98 which carries a vertical post 99, and at the top of this post is a pivot pin 100 for supporting the bellcrank 97. The lateral arms 101 of bellcrank 97 carry magnetic cores or plungers 102 which project into solenoid coils 103 and 104. A contracting coil spring 105 is connected at its upper end to bellcrank 97, and at its lower end to the upright post 99. The tension line or axis of spring 105 is to one side of the pivot axis 100 of bellcrank 97 in either position of the latter. Consequently, when the bellcrank 97 is rocked to one side or the other, it is firmly held in either position by the tensioned spring 105. The lateral extension 95 on frame 85 is provided with a pair of 75 spaced notches 106 and 107 which are preferably

V-shaped. The post 88 or arm 87 carries a latch or plunger 108, which has a bevelled lower end adapted to fit snugly into notches 106 and 107. The latch 108 is supported for vertical movement in a recess 109, which also contains a small expanding coil spring 110 for pushing the plunger 108 downward.

When the solenoid coil 103 is energized, the bellcrank 97 is rocked clockwise (as viewed in Fig. 3) to move the polar projections 91 of magnet 84 into alignment with the first sound track 80. That is to say, when magnet 84 is in the position shown in Fig. 3 during the recording operation, the record track produced by electric impulses in coil 90 will correspond to the position of track 80 in Fig. 8, and this takes place during the forward run of the tape. When the tape runs in the reverse direction as indicated by arrow 83 in Fig. 3, the solenoid coil 104 is energized to rock the bellcrank 97 counterclockwise until the spring-pressed plunger 108 snaps into notch 107. The polar projections 91 are now in position 91' (see Fig. 6) and this position corresponds to the second record track 81 in Fig. 8. It is hardly necessary to say that Figs. 5 and 6 are grossly exaggerated, for the actual device is considerably smaller and the transverse movement of pole pieces 89 is only a small fraction of an inch.

The automatic shifting of magnet 84 simultaneously with the reversal of tape 24 is controlled 30 by a pair of movable switch arms 112 and 113, which are pivoted on pins 114 and 115 carried by bracket arms 116 and 117. The arm 116 may conveniently be secured to the post or standard 88 (see Fig. 7), while the other arm 117 is attached 35 to the upper end of bracket 68. The pivoted switch arm 112 is in the form of a bellcrank carrying at one end a roller 118 and at the other end a contact 119 arranged to engage a stationary insulated contact piece 120 mounted on arm 116 in 40 any practical way. The other pivoted switch arm 113 carries at one end a roller 121 and at the other end a contact 122 arranged to engage a fixed contact piece 123 carried by an insulated strip 124, which is attached to arm 117. Springs 125 45 coiled about pins 114 and 115 normally tend to rock the upper end of switch arms 112 and 113 toward each other, so that the rollers 113 and 121 are pressed against the two edges of tape 24, as shown in Fig. 7 and diagrammatically indicated 50 in Fig. 8. The switch arms 112 and 113 are arranged on opposite sides of the fixed guide plates 92 as close to the field magnet 84 as possible. In Fig. 8 the plane of movement of the electromagnetic recording and reproducing device laterally 55 of tape 24 is diagrammatically indicated by the dotted line 126. To prevent even a very slight lateral movement of tape 24 under the opposing pressure exerted by rollers 118 and 121, the guide plates 92 may be provided with side strips 127 60 which just touch the two edges of the tape as it moves through the guide plates. The edges of these plates are provided with notches 128 for a purpose that will presently be explained. The rollers 118 and 121 are preferably of fiber, rubber 65 or other suitable insulating material.

Referring to Fig. 8, there is a plug 129 adapted to be inserted in a house-lighting socket and connected to a pair of leads 130 and 131, which may include a resistance 132 for reducing the voltage, 70 if necessary. A switch arm 133 is actuated by a cam lever 134 pivoted at 135. A suitable finger piece 136 projecting from the top board 10 of the cabinet is connected to cam lever 134 for moving the same to open and closed position. It is under- 75

stood that the switch parts 133-136 are indicated merely in a diagrammatic way, and in actual practice any kind of on-off switch may be used. The switch arm 133 may be a spring blade normally maintained by inherent tension out of engagement with a stationary contact 131, to which the main conductor 131 is connected. A conductor 138 connects the switch arm 133 with one terminal of the electric motor 33, and the other motor terminal is connected to a wire 139 which leads to one side of a solenoid coil 140. The other side of this coil is connected by a wire 141 to a common terminal 142 which also serves as a binding post for wires 143 and 144. A wire 145 connects the main conductor 130 with the central point 146 of coils 103 and 104, and a wire 147 leads from conductor 130 to the common connecting point 148 of clutch coils 53 and 54. A wire 149 connects one side of coil 54 with one side of coil 104, and a wire 150 connects one side of coil 53 to conductor 144, which leads to the switch contact 123. The fixed contact 120 associated with the movable switch arm 112 is connected by a wire 151 to wire 149, or to one side of coil 104, as indicated at 152. The solenoid coil 140 has a magnetic core 153 pivotally connected to an arm 154, which is secured to (or part of) the hand-operated cam-lever 134. The manual operation of cam lever 134 to on-and-off position 30 is not interfered with by the solenoid core 153. The switch arms 112 and 113, or at least the contacts 119 and 122 thereof, are electrically connected in parallel by wires 155 and 156 to conductor 138. A wire 157 connects the wires 139 and 145. I might explain here that when I speak of a wire in this description, I mean any suitable conductor of electric current, whether in the form of a wire, rod, strip, plate, or other connecting member.

40 The operation of the system illustrated in Fig. 8 is like this, whether used for recording or reproducing. Let us assume that we are recording and that the magnetic tape 24 is running in a forward direction, as indicated by arrow 82. The switch 133 is closed and the pole pieces 89 of magnet 84 are in position to record along the invisible track 80. The rollers 118 and 121 hold the switch arms 112 and 113 against closing as long as the rollers engage the straight edges of the tape. The circuit of motor 33 is closed through switch 133-137, but no current flows through the five coils 53, 54, 103, 104, and 140, because the switch arms 112 and 113 are open. During the recording operation, the coil 90 is subjected to variable current impulses that represent transmitted sound. The circuit connections of coil 90 will presently be explained in detail. The current variations in coil 90 produce corresponding variations of magnetic flux across the air gap between the pole pieces 89. As the magnetic tape 24 is driven at predetermined uniform speed between the pole pieces 89, the flux variations produced by coil 90 are impressed permanently into the magnetic steel of the tape. The resultant record consists of an invisible line or narrow band of steel magnetized permanently with varying intensity corresponding to the recorded sound. This will be understood by those skilled in the art without additional explanation.

60 The magnet 84 may be a permanent magnet whose uniform field is varied by the speech coil 90, or it may be a core of high magnetic permeability with no normal field flux. In the latter case, however, the electric impulses passing

through coil 90 should be sufficiently amplified to produce flux variations of requisite strength.

Still referring to Fig. 8, it will be observed that the tape 24 is provided at its edges with a pair of notches 158 and 159. When the end of the first sound track 80 is reached, the roller 118 on switch arm 112 snaps into notch 158 under the action of spring 125, and contact 119 engages the adjacent contact 120. This closes the circuits of coils 54 and 104, so that the two bellcranks 58 and 97 are simultaneously rocked counterclockwise, as viewed in Fig. 8. The circuit of coil 54 is closed through conductor 130, wire 147 to point 148, coil 54, wires 149 and 151, across the closed switch contacts 120-119, wires 155 and 158, and through switch 133-137 to the return conductor 131. The circuit of coil 104 is closed through conductor 130, wire 145 to point 146, coil 104, wire 151, and so on as above traced for coil 54. When the bellcrank 58 is rocked counterclockwise by the energized coil 54, the clutch gear 52 is shifted into mesh with gear 38 (see Fig. 3), whereby the rotation of sprocket shaft 49 is reversed, so that the tape is now driven in the direction of arrow 83 in Fig. 8. When the bellcrank 97 is rocked counterclockwise by the energized coil 104, the recording magnet 84 is shifted laterally of the tape, so that the pole pieces 89 are now in line with the second track 81 which begins at 81'. Therefore, during the reverse movement of tape 24, which is now wound back on the original pay-out reel 22, the magnet poles 89 will make a magnetic record represented by the track 81 in Fig. 8.

When the end of track 81 is reached, the roller 121 of switch arm 113 snaps into notch 159 in the edge of tape 24 and thereby closes the switch contacts 122-123. This energized simultaneously the three coils 53, 103, and 140. The circuit of coil 53 is closed as follows: from main conductor 130, wire 147 to point 148, through coil 53, wire 150, conductor 144, across the closed switch contacts 123-122, wires 156 and 158, across the closed switch 133-137, and return conductor 131. The circuit of coil 103 is closed through conductor 130, wire 145 to point 146, through coil 103, wire 143 to point 142, conductor 144, and so on as above described for coil 53. The circuit of coil 140 is closed through conductor 130, wires 157 and 139, coil 140, wires 141 and 144, through the closed switch contacts 123-122, and from there to the return conductor 131, as previously traced for coil 53. The energized coil 140 pulls down the core 153 and thereby rocks the cam lever 134 out of engagement with the raised portion 133' of spring arm 133, so that the latter instantly flies to open position and all circuits are broken. This, however, does not happen until after the energized coils 53 and 103 rock their respective bellcranks 58 and 97 to the forward position illustrated in Fig. 8. Consequently, when the machine stops at the end of the recording or reproducing operation, the parts are in position for the forward run of the next tape. The switch lever 134 remains in open position until closed by hand. The notches 128 in guide plates 92 permit the rollers 118 and 121 to snap into the notches 158 and 159 of tape 24. After the tape 24 has once been started in its forward run, the operator need pay no attention to the machine, because the tape is automatically reversed at the end of the first sound track and is automatically stopped when the end of the last track is reached.

In the circuit diagram of Fig. 9, I have shown only so much of the radio receiver system as is necessary to an understanding of this invention. It will therefore be sufficient to say that 160 and 5 161 represent two stages of audio-frequency amplification, and that the loudspeaker L is connected to the final output transformer indicated as a whole by T. This transformer comprises a primary plate coil 162 and two secondary coils 10 163 and 164. The secondary coil 163 is connected to the electromagnetic driving unit 165 of the loudspeaker through wires 166, 167 and 168. The wire 167 is connected to a movable switch arm 169 and wire 168 is connected to a stationary 15 contact 170, which normally is engaged by switch arm 169. In other words, the circuit of loudspeaker coil 163 is normally closed. The secondary coil 164 may be called the recording output coil, because it is operatively connected to 20 the speech coil 90 during the recording operation. One side of coil 164 is connected by wire 171 to a switch arm 172, which normally engages a stationary contact 173. The other side of coil 164 is connected by wire 174 to a switch arm 175, 25 which is normally out of engagement with the associated stationary contact 176. A wire 177 connects contact 176 with a switch arm 178, which normally engages a stationary contact 179. The switch arm 178 is also adapted to connect a 30 pair of stationary contacts 180 and 181. One side of speech coil 90 is connected by wire 182 to contacts 179 and 180, and the other side of that coil is connected by wire 183 to one side of the grid circuit in amplifier stage 160. A wire 184 connects the other side of the grid circuit in amplifier stage 160 to switch contact 181. It is clear 35 from this that when the switch arm 178 is actuated to close contacts 180-181, the speech coil 90 of the recording and reproducing mechanism 40 is shunted across the grid input coil 165.

Still referring to Fig. 9, there is a telephone transmitter 186 connected at one terminal by a wire 187 to one side of plate coil 188 in amplifier stage 160, and the other terminal of the transmitter 45 is connected by wire 189 to a stationary contact 190. The telephone transmitter 186 may be of any approved type or make, as electromagnetic, microphonic, or electrostatic. A movable switch arm 191 associated with contact 190 is connected by wire 192 to the other side of plate coil 188, so that the closing of switch 190-191 connects the telephone transmitter 186 in shunt across the plate coil. The two terminals 193 and 194 at the bottom of Fig. 9 are supposed to 50 be connected to the antenna circuit of the radio receiver, and these terminals are connected by a pair of normally closed switches 195-196 and 197-198, which are connected in series by wire 199. The switch members 195 and 197 are movable arms normally engaging the associated contacts 196 and 198. When either of these switches is open, the electric connection between terminals 193 and 194 is broken and the radio receiver system is disconnected from the antenna. The 55 reason for this will presently be explained. The three switch arms 191, 169, and 195 at the left of Fig. 9, and the three switch arms 172, 178 and 179 at the right of the figure, may each consist of a single spring blade which is normally held 60 by inherent set or tension in the position shown in the drawings. That is to say, the two left spring arms 169 and 195 and the two right spring arms 172 and 197 normally engage their associated contacts. The spring arm 178 normally engages contact 179 while out of engagement with

the adjacent pair of contacts 180-181. The six spring blades referred to are each provided with a hump or cam projection 200, but the spring arm 175 carries an insulating block 201 with a V-shaped cam groove 202.

The four switch arms 191, 169, 175, and 195 at the left of Fig. 9 are simultaneously controlled by a pivoted lever 203 adapted to be operated by a finger piece 204, which is supposed to be located in a convenient position on cabinet C. It may be assumed that the switch-operating lever 203 is of the snap-over type, which moves quickly from one position to the other to make and break the circuit. The lever 203 occupies three positions, as indicated by suitable notations on the cabinet 15 adjacent the finger piece 204. In normal or "off" position of lever 203, the switch arms 191, 169, 175, and 195 are in the position shown in Fig. 9. When the finger piece 204 is moved to "Home recording" position, the tip of lever 203 is swung to 20 the left and engages the humps 200 of arms 191, 169, and 195, and also engages the cam block 201 of switch arm 175, so that these four switch arms are simultaneously depressed. The result of this operation is the closing of switches 190-191 and 25 175-176, and the opening of switches 169-170 and 195-196. When the finger piece 204 is moved left to "Radio recording" position, the only switch arm actuated is 175, because the V-shaped groove 202 of cam block 201 causes this 30 arm to be moved to closed position when the lever 203 swings either way. The movements of lever 203 are limited by stops 205 or otherwise.

The three switch arms 172, 178, and 197 at the right of Fig. 9 are simultaneously operated by a 35 pivoted lever 206, which is controlled by a suitable finger piece 207 projecting from the cabinet. Stops 208 limit the movement of lever 206 in either direction. As long as the finger piece 207 remains in "off" position, the switch arms 172, 40 178, and 197 engage their respective contacts 173, 179, and 198. When the finger piece 207 is snapped to "on" position, the lever 206 swings to the left and engages the humps 200 of the associated switch arms, which are thereby moved 45 to open position. When the switch arm 178 is depressed, it connects the adjacent contacts 180-181 to connect the speech coil 90 across the input coil 185 of the radio receiver. It will be understood that the arrangement of the seven 50 switch arms in Fig. 9 is merely diagrammatic, so as to facilitate the drawing of the circuit wires. In the actual device, the four switch arms at the left may be arranged side-by-side on a single insulating block, so as to be operated simultaneously by cam lever 203. The same remark applies to the three switch arms at the right of Fig. 9 and the associated cam lever 206.

When the finger pieces 204 and 207 are in normal "off" position, the recording and reproducing mechanism is disconnected and the receiver operates in the usual way to reproduce the received broadcast through the loudspeaker L. Let us suppose that a person wants to make a record of a certain broadcast number. Assuming that 65 the recording apparatus is loaded with a recording tape or film, it is only necessary to snap the finger piece 204 to "Radio recording" position, whereby the switch 175-176 is closed to connect the speech coil 90 of the recording mechanism 70 in circuit with the secondary output coil 164. This circuit may be traced as follows: starting at one side of coil 164, through wire 171, across the closed switch 172-173, wire 209, coil 90, wire 182, contact 179, switch arm 178, wire 177, across 75

the closed switch 176—175, and through wire 174 back to the other side of coil 164. The amplified impulses in the primary output coil 162 induce corresponding impulses in the secondary coils 163 and 164 for simultaneously actuating the loudspeaker L and the recording mechanism. Therefore, while the loudspeaker is audibly reproducing a broadcast reception, the recording mechanism is silently making a record of what is heard through the loudspeaker. To stop the recording operation, the finger piece 204 is moved to "off" position.

It is also possible to operate the recording mechanism to make a record of speech or music originating in the home. In this case the transmitter 186 is used in the same way as when a person talks or sings into a telephone. The transmitter 186 may be located at any distance from the recording apparatus. For making home records, a person moves the finger piece 204 to "Home recording" position, whereby the transmitter 186 is connected across the grid input coil 185 and the loudspeaker L is disconnected. As previously explained, when the finger piece 204 is moved to "Home recording" position, the cam lever 203 closes the switch arms 191 and 175, and at the same time opens the switch arms 169 and 195. The opening of switch arm 195 interrupts the connection between terminals 193 and 194, so that the radio receiver is disconnected from the antenna circuit and is in no condition to receive any broadcast. The closing of switch 190—191 connects the telephone transmitter 186 across the plate coil 188, so that the current impulses produced by the vibrations of the transmitter diaphragm are superimposed upon the normal plate current in coil 188. These impulses are amplified through one or more stages until they reach the final output coil 162. The opening of switch 169—170 breaks the circuit of loudspeaker coil 163, so that the loudspeaker is out of commission during the recording operation. The secondary coil 164, however, is connected in circuit with speech coil 90, because the switch 175—176 is now closed. Therefore, the amplified current impulses in plate coil 162 induce corresponding impulses in secondary coil 164 to energize the speech coil 90, which records the electric impulses on the moving tape or film 24, as previously explained.

After a record has been made in the manner above described, a person can reproduce the recorded sound waves through loudspeaker L by merely shifting the finger piece 207 to "on" position, whereby the normally closed switches 172—173, 178—179, and 197—198 are automatically opened, and the normally open contacts 180—181 are connected by switch arm 178. The opening of switch 172—173 cuts the secondary recording coil 164 out of circuit, and the opening of switch 197—198 disconnects the radio receiver from the antenna. The closing of contacts 180—181 connects the speech coil 90 across the input coil 185. Consequently, when the tape or film 24 is run through the machine, the previously made record produces electric current impulses in coil 90, and these impulses are impressed upon the grid circuit of amplifier stage 160. The operation of the receiver system is the same as if the electric impulses in coil 90 had been received from the antenna. The impulses generated in coil 90 by the record on the tape or film 24, are sufficiently amplified in the final output coil 162 to operate the loudspeaker L at requisite volume.

75 It will now be apparent that I have produced a

comparatively simple apparatus for utilizing the circuits of a radio receiver to record broadcast reception without interfering with the normal operation of the receiver through the loudspeaker. The movement of a single finger piece is enough to place the apparatus in condition for recording the voice of any person who speaks or sings into the telephone transmitter at 186. To reproduce a previously made record through the loudspeaker of the radio receiver, it is only necessary to close the switch member 207. It will be clear to those skilled in the art that the circuit diagrams in Figs. 8 and 9 go together, but I considered it advisable to separate them so as to prevent confusion in drawing the circuit lines, and also to facilitate a description of the invention. In the actual machine the finger piece 204, when moving to either of its recording positions, also closes the switch 133—137 in Fig. 8, so that no separate finger piece 136 is necessary. Also, when the reproducing switch 207 is closed, the switch arm 133 is simultaneously moved to closed position.

In the basic aspect of my invention, any practical form of recording and reproducing mechanism may be used. The tape 24 may be either a 25 magnetic ribbon or a photographic film. In the optical method of recording and reproducing, the speech coil 90 is so connected that the current impulses passing therethrough cause corresponding 30 variations in the intensity or quantity of light to 35 which the photographic film is subjected. This will be clear to those who are familiar with the making of sound records on films. When I use the word "tape" in the claims without further qualification, I mean any flexible ribbon-like member 40 on which sound can be recorded. The speech coil 90 may also be used to operate a recording stylus which cuts a spiral track in a wax record, but this method of recording is too complicated 45 for home use. I do not wish to be understood, however, as excluding the wax-cutting method of recording from the purview of my invention. It is evident that in the practical embodiment of my combination radio-recording-reproducing cabinet, various changes and modifications may be resorted to without departing from the scope of the 50 invention as defined in the appended claims.

I claim as my invention:

1. Recording mechanism comprising a magnetic tape mounted to run in alternately opposite 50 directions, an electromagnetic device controlled by electric impulses for making a plurality of magnetic record tracks on said tape, means for automatically reversing the movement of said tape at the end of a record track, and means for shifting 55 said device laterally of the tape when the latter is reversed.

2. An electromagnetic recording and reproducing device comprising a magnetic tape supported for movement in either direction, a pair of stationary non-magnetic plates spaced to receive said tape in a snug fit, and an electromagnetic device having a pair of pole pieces in axial alignment and arranged to touch the outer faces of said plates, whereby the moving tape is always at the 60 same distance from the adjacent faces of said pole pieces.

3. An electromagnetic recording and reproducing device comprising a magnetic tape supported for movement in either direction, a pair of stationary non-magnetic plates spaced to receive said tape in a snug fit, an electromagnetic device having a pair of pole pieces in axial alignment and arranged to touch the outer faces of said plates, whereby the moving tape is always at the same 70 75

distance from the adjacent faces of said pole pieces, and means for moving said pole pieces laterally of said plates.

4. The combination of a radio receiver having an input circuit and two independent output circuits, a loudspeaker connected to one of said output circuits, recording mechanism connected to the other output circuit, said mechanism including a telephone transmitter adapted to be connected to said input circuit, switch means for closing both of said output circuits to record broadcast reception while it is reproduced through said loudspeaker, and switch means for closing only said other output circuit to operate said recording mechanism through said transmitter while the radio receiver and loudspeaker are incapable of broadcast reception.

5. A radio-phonograph cabinet containing a radio receiver and a loudspeaker, phonographic recording and reproducing mechanism in said cabinet comprising a flexible tape for receiving a plurality of record tracks which run in alternately opposite directions, said recording mechanism including a telephone transmitter connected by wire to the cabinet, means for operating said tape simultaneously with the radio receiver to record broadcast reception, and means for operatively

connecting said transmitter and tape to record the sound waves actuating said transmitter while the receiver is inoperative, the amplifying system of said receiver being used in both of said recording operations and in the reproducing operation of said phonographic mechanism.

6. The combination of a radio receiver having an audio frequency amplifying system inclusive of input and output circuits, a recording and reproducing device common to both circuits, said device having an operating coil, a loudspeaker adapted for connection with the output circuit, means for connecting said coil with the input circuit to record broadcast reception without interfering with the usual operation of said loudspeaker, a transmitter adapted for direct connection with the input circuit as distinguished from locating said transmitter at a distance from the system and utilizing radio waves as a means for operatively connecting the same with the system, means for connecting said coil with the input circuit to record broadcast reception when the transmitter is disconnected, and means whereby the operative connection of the transmitter with said coil through said system automatically disables said loudspeaker.

ADOLPH A. THOMAS.
